UNITED STATES PATENT OFFICE.

AUGUSTE ARTHUR CAILLE, OF DETROIT, MICHIGAN.

COIN-CONTROLLED LIFTING-MACHINE.

SPECIFICATION forming part of Letters Patent No. 783,678, dated February 28, 1905.

Application filed April 4, 1904. Serial No. 201,478.

To all whom it may concern.

Be it known that I, AUGUSTE ARTHUR CAILLE, a citizen of the United States of America, residing at Detroit, in the county of Wayne and State of Michigan, have invented certain new and useful Improvements in Coin-Controlled Lifting-Machines, of which the following is a specification, reference being had therein to the accompanying drawings.

10 This invention relates to improvements in coin-controlled lifting-machines; and its object is to provide a simple, cheap, and efficient construction which is not liable to get out of order or be broken; and to this end the invention 15 consists in the novel construction, arrangement, and combination of parts, all as herein-after more fully described, and shown in the accompanying drawings, in which—

Figures 1 and 2 conjointly form a transverse 20 vertical section of the vertical casing of a device embodying the invention, showing the operating mechanism in elevation looking from the rear of the machine. Fig. 3 is a longitudinal vertical section of the same with the 25 middle portion of the casing broken away for the purpose of shortening the figure. Fig. 4 is a detail showing the locking mechanism in elevation; Fig. 5, an edge view of the same; Fig. 6, a section on the line *x x* of Fig. 4, and 30 Fig. 7 an elevation showing the parts in a different position from that shown in Fig. 4.

A is the base, from the rear end of which rises the vertical casing B, and on the upper end of this casing is secured the head or indicator-casing C. From the forward end of the 35 base rises a hollow post A', within which is the longitudinally - movable draft-rod 1, screw-threaded at its upper end for the engagement of an adjustable handle 2 and at its lower end 40 provided with a washer 3, held thereon by a transverse pin, said washer engaging the lower edge of the forked end of a lever 4, located in the base. The opposite end of said lever 4 engages an opening in a hook 5, attached to the 45 lower end of a heavy coiled spring 6, adjustably supported at its upper end by a hook 7, the screw-threaded shank of which passes through an opening in a bracket secured to the forward side of the casing B and provided 50 with a nut engaging the upper side of the

bracket. A knife-edge pivot-bearing 8 on the base engages the upper edge of the lever 4 intermediate its ends, and a screw-threaded sleeve 9 on the rod 1 engages the upper end of the post A' to limit the downward movement of said rod, so that the lever 4 is held at all times by the spring 6 against its bearing 8 to rock thereon. 55

Secured within the indicator-casing C is a dial 10, provided with suitable graduations, and projecting in the axis of this dial is a short shaft 11, to the end of which an indicator hand or pointer 12 is secured to point off on the dial the number of pounds lifted by the operator against the action of the spring 6. 60 To turn this shaft and its pointer, a sprocket-wheel 13 is secured to the shaft, and this sprocket-wheel is engaged by a sprocket-chain 14, attached at one end to a coiled spring 15, secured at the opposite end to the casing, and 65 the opposite end of the chain is attached to a wire 16, which is attached to the vertically-movable bar 17 of the coin-controlled locking mechanism 18. The lower end of the bar 17 is connected by a wire 19 to a laterally-extending arm 20 on the end of the lever 4, so that as the operator pulls upward on the handle 70 the downward movement of said end will pull on the chain against the action of the spring 15 and turn the indicating-hand. To prevent 75 the hand from being turned backward by said spring as soon as the handle is released by the operator, the locking mechanism 18 is provided, and operating in conjunction with said mechanism to lock the lever 4 and its handle 80 against being operated until a coin is inserted to release the locking mechanism, a hook 21 is pivotally secured to the casing above the arm 20 and falls by gravity into engagement with said arm, hooking beneath the same. 85

The coin-controlled locking mechanism 18 consists of a base-plate 22, secured to the wall of the casing and provided with ears 23, having openings to receive the vertically-movable bar 17 and forming bearings therefor, within 90 which it is guided and freely movable. Secured to the lower end of said bar 17 is a sheet-metal flange 24, provided with an opening through which the rod or wire 19 extends, said wire being bent at right angles near its 100

upper end to engage the flange when the wire is moved by the movement of the lever 4 and move said bar longitudinally downward. As shown in Fig. 4, the bar is locked in the position to which it is moved by the rod 19 by a cam-lever 25, provided with a rounded shoulder 26 to engage the edge of the bar and pivoted at 27 to one end of a flat lever 28, which lever is in turn pivoted intermediate its ends at 29 to the base-plate 22, the opposite end of said lever projecting beneath the bar 17. On the upper edge of the lever 28 is a post 30, and on the lower edge of the cam-lever is a similar post, to which posts the ends 10 of a coiled spring 31 are attached to normally hold the upper edge of the cam-lever against the post 30, which thus forms a stop therefor, and on an upwardly-projecting portion of the base-plate is a post, to which one end of a 15 coiled spring 32 is attached, its opposite end being attached to the lever 28 between its pivot 29 and its end to which the cam-lever is pivoted to turn said lever 28 on its pivot. On the end of the lever 28 adjacent to the 20 pivot 27 is a projecting shoulder 33, adapted to be engaged by a weighted latch 34, pivoted intermediate its ends at 35 and having an upwardly-projecting hook 36, an arm forming a weight 37 at one side of the pivot, and a laterally-projecting arm 38 at the opposite side 25 of the pivot to project into the coin-chute 39, so that a coin inserted in the chute will fall upon the end of said arm 38 and rock the latch on its pivot to release the lever 28, which will then be turned on its pivot by the 30 spring 32 until a projection on its lower edge 35 engages a stop 40 on the base-plate.

As soon as the latch 34 is operated by a coin to release the lever 28 the cam-lever 25 40 will be turned, with the lever 28, upon its pivot 29 away from the bar 17 and will be engaged by the post 30 and held with its cam-shoulder 26 out of engagement with said bar, thus releasing the same and allowing the coiled spring 45 15, through the medium of the chain 14 and rod 16, to lift the said bar to the position shown in Figs. 1 and 2 and in dotted lines in Fig. 4, this movement of the chain operating to return the indicating-hand back to zero from 50 the position to which it had been turned by a previous lift or operation of the machine.

On the bar 17 is formed a lug 41, projecting toward the base-plate, and in the edge of the bar adjacent to said lug is formed a slight 55 depression 42, so that when said bar is released and raised said lug will engage the ends of the levers 25 and 28, projecting beneath said bar, and turn the same upon the pivot 29, thus allowing the latch 34 to reengage the 60 shoulder 33, said depression allowing the cam-lever to be turned, with the lever 28, into the position shown in Fig. 1. In this position of the parts the machine may be again operated and will indicate on the dial the number of 65 pounds lifted, as when the lever 4 is rocked

on its pivot-bearing the rod 19 will be moved downward, thus moving the bar 17, as said bar is not locked against downward movement by the cam-lever, which upon such movement will be turned on its pivot 27 against the action of the spring 31. The bar 17 will, however, be prevented by said cam-lever from being raised by the spring 15 upon the release of the handles by the operator, as its rounded end or shoulder 26 is held in contact with the 75 edge of the bar by the spring 31 at a point slightly below a horizontal line drawn through its pivot 27, and therefore said cam-lever forms a wedge between its pivot and the bar to hold the bar against upward movement in its bearings. 80

The parts as shown in full lines in Fig. 4 are in the position in which they are left after each operation, and to prevent the machine from being again operated without first putting in a coin the gravity-hook 21, before described, is provided, which hook is operated to release the arm 20 and allow the machine to be operated by providing said hook with a projecting arm or lug 43, to which one end 90 of a wire or rod 44 is attached, the opposite end of said wire being extended through an opening in the flange 24 on the lower end of the bar 17 and bent at right angles to engage the upper side of said flange. This rod 44 is 95 of such a length that when the bar 17 is in the position shown in Fig. 1 or after having been released by the dropping of a coin and raised by the spring 15 the hook 21 will be raised out of contact with the arm 20, and thus the indicator is turned to zero and the lever 4 released by the dropping of the coin. Said hook 21 being suspended from the flange 24 when the bar 17 is in its raised position, as soon as said bar is lowered the hook will 100 fall by gravity, and as the rod 19 by the engagement of its bent end with said flange is the medium for moving said bar it is necessary that said rod be made of such a length that the arm 20 may be moved downward a short distance past the shoulder of the hook before the bent end of said rod will engage the flange and move the bar 17 to allow the hook to fall. A stop 45 on the hook limits its movement, so that when the operator lets 110 up on the handle the arm 20 will engage and pass the hook, which will fall by gravity into engagement with the arm and lock the same until the hook is again raised out of contact therewith by the coin-actuated mechanism. 115

Secured to the casing below the locking mechanism is a plate 46, upon which is supported a bell 47, and on the plate is pivotally mounted an arm 48, carrying the bell-hammer, said arm being turned against the action of a 12 spring to actuate the hammer by a laterally-extending pivoted dog 49, adapted to be engaged by the flange 24 on the downward movement of the bar 17, said dog being so positioned relative to the bar that the bell will be 130

sounded when the indicator has been turned to a certain predetermined point or when a certain amount has been lifted by the operator.

The parts being constructed and arranged as described, they are intended to operate as follows: When a coin is inserted, the bar 17 is released and is lifted by the spring 15, returning the indicator-hand to zero and through the medium of the rod 44 lifting the hook 21 out of the path of the arm 20, all as hereinbefore described, and therefore when the operator lifts on the handle, thus rocking the lever 4 on its bearing against the action of the spring 6, the arm 20 on said lever will be moved downward, carrying with it the rod 19, the upper bent end of which rod will engage the flange 24 after said arm has passed the shoulder of the hook 21 and will pull the bar 17 downward. This downward movement of said bar turns the indicator-hand against the action of the spring 15, and said hand is held in that position by the cam-lever 25, which prevents the bar from being moved upward until another coin is dropped in, the cam-lever, as previously described, having been again set by the upward movement of the bar after having released the same upon the insertion of the previous coin. Upon the release of the lifting-handle by the operator the end of the lever carrying the arm 20 is raised by the spring 6, and as the hook 21 was permitted to fall by its own gravity into the path of said arm when the bar 17 was pulled downward by the previous downward movement of the arm said hook will be engaged and turned by the arm as the same moves upward and will hook beneath said arm, preventing any further manipulation whatever of the device until another coin is inserted. If it were not for the hook, any number of lifts might be made without inserting more than one coin, as the lever 4 would be free and the indicator would be turned each time, provided the last lift was greater than the one before.

Having thus fully described my invention, what I claim is—

1. In a lifting-machine the combination with a lever pivoted intermediate its ends, handles attached to one end of said lever by means of which the lever is turned on its pivot, and a spring to resist the movement of the lever; of a gravity-hook normally engaging the lever to prevent the movement of the same by means of the handles, and coin-controlled means for lifting the hook out of contact with the lever to release the same and permit its operation by the handles.

2. In a lifting-machine, the combination with the lifting-handles, a lever to which the handles are connected, and a spring for resisting the movement of said lever; of an indicator, means connecting the indicator and lever to turn the former upon the movement of the latter, coin-controlled locking mechan-

ism to hold the indicator in the position to which it is turned and adapted to be operated by a coin to release the same, and means for engaging said lever to prevent the movement of the handles, said means being connected to the locking mechanism and operated thereby to release the lever.

3. In a lifting-machine, the combination with the lifting-handles, a lever to which the handles are connected and a spring for resisting the movement of said lever; of an indicator operated by the movement of the lever, coin-controlled locking mechanism to hold the indicator in the position to which it is turned by the lever and adapted to be operated by a coin to release the same, a hook to engage the lever and prevent the movement of the handles, and means connecting said hook and locking mechanism whereby when the mechanism is operated by a coin to release the indicator, the hook will be disengaged from the lever to permit the movement of the handles.

4. In a lifting-machine, the combination with lifting-handles, a lever connected at one end to said handles, and a spring connected to the other end of said lever to resist the movement of the handles; of a locking member to engage the lever and prevent the movement of the lever and handles, an indicator, a longitudinally-movable bar to actuate the indicator and connected to the lever to be moved in one direction thereby, spring to move said bar in the other direction, coin-controlled locking mechanism for holding the bar in the position to which it is moved by the movement of the lever and means connecting the bar and locking member to operate said member to release the lever when the bar is released by the locking mechanism and moved by the spring.

5. In a lifting-machine, the combination with a movable member adapted to be actuated by the operator, of an indicator, a longitudinally-movable bar, means for actuating the indicator attached to one end of said bar, means for actuating said bar in one direction engaging the opposite end thereof and attached to the movable member, a spring to actuate the bar in the opposite direction, a cam-lever to engage the bar and prevent the movement thereof in one direction, a latch to hold said lever in engagement with the bar, a coin-chute, and an arm on said latch projecting into the chute and adapted to be engaged by a coin to release the latch.

6. In a lifting-machine, the combination with a movable member adapted to be actuated by the operator, of an indicator, a longitudinally-movable bar, means attached to one end of said bar for actuating the indicator, a spring to move the bar in one direction, means connecting the opposite end of the bar and the movable member to move the bar in the opposite direction, a pivoted lever, a cam-lever pivoted at one end to the end of said lever, a spring to hold the cam-lever in engagement

with the bar, a latch to engage the pivoted lever, a coin-chute, an arm on said latch projecting into the coin-chute, and a spring to turn said lever upon its pivot when released by the latch to move the cam-lever out of contact with the bar.

7. In a lifting-machine, the combination with a movable member adapted to be actuated by the operator, of an indicator, a longitudinally-movable bar, means attached to one end of said bar for actuating the indicator, a spring to move said bar in one direction, means connecting the opposite end of said bar and the movable member to move the bar in the opposite direction, a lever pivoted intermediate its ends, a stop on said lever, a cam-lever pivoted at one end to the end of the said lever farthest from said bar, a spring to hold the cam-lever in engagement with the bar, a latch to engage the intermediately-pivoted lever, a coin-chute, an arm on the latch projecting into the chute, a spring to turn the pivoted lever when disengaged by said latch, and a lug on the bar to engage said levers and turn the same into position to be reengaged by the latch when the bar is moved by its spring.
8. In a lifting-machine, the combination of a vertically-movable rod, a handle on said rod, a lever attached to and operated by said rod, a spring attached to the opposite end of said lever, a gravity-hook to engage and prevent the operation of said lever, a vertically-movable bar guided in bearings and provided with a flange at its lower end having openings, a spring to move said bar vertically upward, coin-controlled locking mechanism to prevent the upward movement of the bar, a wire rod secured at its lower end to said lever and extending upward through one of the openings in the flange on said bar and provided with a laterally-bent end to engage said flange, said rod being of a length to extend a short distance through the flange so that the lever may be moved a short distance before the laterally-bent end of the rod will engage the flange to move the bar, and a wire rod attached at one end to the hook and extended upward through the other opening in the flange and bent laterally at its upper end to engage the flange, said rod being of such a length that when the bar is raised by its spring to its highest position, the hook will be lifted thereby out of the path of the lever.

9. In a lifting-machine, the combination with a base portion and a vertically-extending casing, of a vertically-extending rod guided in the base, a handle on said rod, a lever attached at one end to the lower end of said rod and engaged intermediate its ends by a bearing on the base, a spring attached to the opposite end of said lever, a hook engaging the opposite end of said spring and having a screw-threaded shank, a bracket on the casing having an opening to receive the shank, a nut on the shank engaging the upper side of the bracket, an arm extending laterally from the side of said lever, a gravity-hook secured to the casing to engage said arm, a stop on said hook, an indicator-dial upon the upper end of the casing, a shaft in the axis of said dial, an indicator-hand on said shaft, a sprocket-wheel on said shaft, a sprocket-chain engaging said sprocket, a spring attached at one end to the casing and at its opposite end to one end of the chain, a plate secured to the casing, a vertically-movable bar mounted in bearings on said plate and connected at its upper end with the opposite end of said chain, a flange on the lower end of said bar having openings, wire rods having laterally-bent upper ends extending downward through the openings in the flange and attached respectively to the arm on the lever and to the hook, a bell secured to the casing below the said plate, a lever provided with a hammer and adapted to be engaged by the said flange when said bar is lowered, a coin-chute having an opening, a lever pivoted on the said plate intermediate its ends with one end extending beneath the bar, a cam-lever provided with a cam-face to engage the edge of the bar and pivoted at its opposite end to the pivoted lever, a stop on the pivoted lever, a spring to hold the cam-lever in engagement with the bar, a weighted latch to engage the pivoted lever and having an arm extending through the opening in the coin-chute, a spring to turn the pivoted lever, and a lug on the said bar to engage the pivoted and cam levers.

In testimony whereof I affix my signature in presence of two witnesses.

AUGUSTE ARTHUR CAILLE.
